United States Patent Office

Des. 186,828
Patented Dec. 8, 1959

186,828

BUOY TACKLE BOX

William D. Cornett, Port Lavaca, Tex.

Application January 20, 1959, Serial No. 54,257

Term of patent 14 years

(Cl. D58—11)

Fig. 1 is an elevational view of one side of a buoy tackle box showing my new design;

Fig. 2 is an elevational view taken from the right of Fig. 1;

Fig. 3 is a plan view thereof; and

Fig. 4 is a bottom view thereof.

I claim:

The ornamental design for a buoy tackle box, as shown.
